United States Patent Office

Des. 214,902
Patented Aug. 12, 1969

214,902

BATHTUB

Jack A. Goodall, Dallas, Tex., assignor, by mesne assignments, to Venetian International, Inc., Dallas, Tex., a corporation of Texas

Filed June 20, 1968, Ser. No. 12,445

Term of patent 14 years

Int. Cl. D23—02

U.S. Cl. D23—55

FIG. 1

FIG. 3

FIG. 2

FIG. 4

FIGURE 1 is a perspective view of a bathtub showing my new design;

FIGURE 2 is a top plan view thereof;

FIGURE 3 is a cross sectional view taken on line 3—3 of FIGURE 2; and

FIGURE 4 is a cross sectional view taken on line 4—4 of FIGURE 2.

The fragmentary broken line representation of a top panel therefor in FIGURE 1 is for purposes of illustration only.

I claim:

The ornamental design for a bathtub, as shown and described.
